Primary Examiner — Susan Bennett Hattan*Assistant Examiner* — Rebecca Tsehay(74) *Attorney, Agent, or Firm* — Seager, Tufte & Wickhem LLP(57) **CLAIM**

The ornamental design for a brush cleansing mitt, as shown and described.

DESCRIPTION

FIG. 1 is a perspective view of a brush cleansing mitt showing the new design;

FIG. 2 is a front elevation view of the brush cleansing mitt of FIG. 1;

FIG. 3 is a back view of the brush cleansing mitt of FIG. 1; FIG. 4 is a right side view of the brush cleansing mitt of FIG. 1, the left side view of the brush cleansing mitt being a mirror image of the right side view;

FIG. 5 is a top view of the brush cleansing mitt of FIG. 1; and,

FIG. 6 is a bottom view of the brush cleansing mitt of FIG. 1.

The broken lines in the drawing depict portions of the brush cleaning mitt that form no part of the claimed design.
